SUCTION INTENSIFIER

Application filed August 3, 1929. Serial No. 383,191.

This invention relates to a suction intensifier or augmenter for boosting the influence of manifold suction on automobile accessories, the construction herein being an improvement on the disclosure made in the co-pending application for patent on a suction augmenting device filed April 2, 1928, Serial No. 266,839 in the name of Henry Hueber.

Pressure variations, in the intake manifold 10 of motor vehicle engines, are quite marked and noticeable in their influence and effect on the operation of an accessory such as a windshield cleaner. Thus when the engine is throttled the manifold suction supply is 15 quite ample and efficient whereas when the intake manifold is more or less fully opened and the engine laboring, the degree of manifold suction is insufficient to operate the accessory at the desired normal. The advantage 20 of an augmenting device for intensifying or boosting the manifold suction when of an inefficient degree is, therefore, quite obvious. The introduction of the venturi in the suction line of a windshield cleaner 25 has the effect of boosting an inefficient supply of manifold suction to a practical degree. In the above referred to application means are provided for avoiding the action of the venturi or intensifier when the manifold suction has reached or exceeds a practical 30 degree.

The primary aim of this invention is to simplify and compact the construction of the intensifier into a more practical assembly, and 35 one which provides ample protection for the moving and sensitive parts of the mechanism.

The invention further resides in mounting the Venturi control valve as a unit with the 40 suction responsive member or piston, the entire unit being self-contained and adapted for placement and displacement as a unit in and from the assembly.

The invention is also found to reside in the 45 mounting of the valve on the piston and also in the resilient mounting of the piston in its cylinder or chamber, as will be more fully pointed out in the description and appended claims, reference being made to the accompanying drawings wherein,

Fig. 1 is a vertical sectional view through the intensifier construction in accordance with the present invention.

Fig. 2 is a plan view thereof with a part of the cover plate broken away so as to show 55 more clearly the underlying mechanism.

Fig. 3 is a detailed perspective view of the valve-piston unit.

Proceeding in accordance with the present invention, the numeral 1 designates the body 60 of the intensifier through which extends a venturi passage consisting of an inlet port 2 provided in the nozzle member 3, a spaced and flaring outlet or delivery passage 4, and an interposed aspirator or induction chamber 5 leading to an induced flow port 6 designed for connection to a suction operated mechanism or accessory, such as the windshield cleaner of a motor vehicle. The delivery passage 4 is designed for connection to the intake manifold of the motor vehicle engine. 65

The intensifier is provided with a chamber 7 which receives a pressure responsive member, said chamber being provided with a port 8 for establishing communication with the delivery passage 4. Within the chamber may be disposed a bushing 9 so as to provide for a better sliding fit of the pressure responsive member or piston 10, which latter has its piston rod or stem reduced, as at 11, 70 for being received in the slot 12 formed in the extension 13 of the control valve 14. The valve is preferably of the disc type and is designed for seating on the outer end of nozzle member 3. 75

Normally the valve is urged from its seat by spring means which also function to lift the piston in its chamber 7 against the action of an inefficient supply of manifold suction to thereby open the nozzle passage 2 and set the intensifier in action. To make the piston and valve assembly complete in itself this spring 15 is incorporated in the unit and is herein depicted as coiling about the piston rod 16 beneath the reduced portion 11. 80

As a support for the lower or inner end of the spring there is provided a plate 17 through which the piston rod has free sliding movement and which is itself of sufficient di- 100

mension to engage and seat on a supporting shoulder 18, as its provided by the outer end of the bushing 9. The opening in the plate 17 is of smaller diameter than the piston itself so that when the piston is removed from its chamber or cylinder the plate will be lifted out by the underlying piston 10 so that the entire assembly is self-contained and can not be disrupted without first displacing the 10 valve laterally, or disengaging the reduced portion 11 from the slot 12, whereupon the spring 15 and the plate 17 may be axially displaced from the piston rod.

A cover plate 19 is mounted on the 15 standing and surrounding wall 20 of the body 1 and is secured in position by a pair of fastening elements one of which is indicated at 21. The surrounding wall 20 encloses the space 22 and defines a valve chamber which is 20 open to the atmosphere, as through openings 23 provided in the cover plate 19.

With the parts related as shown in Fig. 1 25 the Venturi passage of the intensifier is rendered inoperative by reason of an efficient or excessive supply of manifold suction maintaining in the manifold or the outlet side of the intensifier, and in this position the piston or fluid pressure responsive member 10 is held depressed by reason of the low pressure 30 maintaining in the chamber 7 beneath the piston, which is of such a degree that the atmospheric pressure operating on the exterior side of the piston will overcome the resiliency of the spring 15 and cause the valve 14 to 35 seat over the port 2. The manifold suction will then act in its entirety upon the windshield cleaner motor or other accessory.

When the manifold suction becomes inefficient and the pressure in the chamber 7 beneath the piston 10 approaches the atmospheric pressure the spring 15 will cause the valve 14 to lift from its seat whereupon the atmospheric air will enter through the nozzle 3 and induce a higher degree of suction 40 in the chamber 5 than that which maintains at the manifold side of the intensifier. Such lifted or inoperative position of the valve is indicated by the dotted showing in Fig. 1.

The entire assembly of the intensifier has 45 been compacted and simplified. It is easily disassembled for repair, and is thoroughly protected against exposure of its operating parts. The cover 19 acts as a means for preventing displacement of the valve-piston unit entirely from the intensifier chamber, and may serve to prevent outward displacement beyond the range of influence of an excessive degree of manifold suction. The 55 valve-piston unit is simple in design, the spring acting secondarily to frictionally hold the extension 13 from working laterally and becoming dislodged from the reduced portion 11 of the piston rod or stem.

In placing the unit within the intensifier 60 body it is only necessary to position the pis-

ton in the chamber 7 and as the piston descends within the latter the spring-supporting plate 17 will engage the shoulder 18 and resiliently arrest and support the piston. The valve is supported wholly by the piston 70 and is bodily moved thereby during operation.

What is claimed is:

1. A suction intensifier for the suction lines of automobile accessories, comprising a body 75 having an injector nozzle discharging across an aspirator chamber into a deliver passage, a cylinder formed in the body and having its inner end communicating with the delivery passage, a piston operable in the cylinder, a valve having an extension provided with a slot, a piston rod connected to the piston and having a part receivable in the slot of said valve extension for detachably connecting the valve to the piston to be operated thereby, and resilient means carried by the piston rod and engaging a fixed part of the body for resiliently supporting the valve and piston as a unit.

2. A suction intensifier for windshield 90 cleaners, comprising a unitary body having a Venturi passage therethrough and a chamber communicating with the outlet side thereof, a valve for controlling the passage of atmospheric air through the injector portion 95 of the Venturi passage, a pressure responsive member operable in the chamber and having a rod, said valve having a part engaging said rod for supporting the valve from the rod for bodily movement as a unit therewith, a spring encircling the rod beneath the valve part, and a spring supporting plate slidably receiving the rod and supporting the adjacent end of the spring, said body having a shoulder on which said plate engages to co-act with the spring in resiliently supporting said member.

3. A suction intensifier comprising a body having an injector nozzle, a delivery passage, and an interposed aspirator chamber, said body also having a valve chamber surrounding the outer end of the nozzle, a cylinder communicating at its inner end with the delivery passage, a piston operable in the cylinder and having a rod extending into the valve chamber, a valve arranged in said valve chamber and movable to close the outer end of the nozzle, said piston rod constituting the sole means of support for the valve, and spring means arranged on the piston rod beneath the valve extension for resiliently supporting the valve and piston as a unit from a fixed part of the body.

4. A suction intensifier comprising a unitary body having a cylinder, a piston operable in the cylinder, a delivery passage in the body with which the cylinder communicates, an injector nozzle in the body discharging into the passage and defining with said passage an aspirator chamber, a valve for open- 120 125 130

ing and closing said injector nozzle and supported by said piston, means connecting the piston and valve as a unit, and means embodied in said unit and removable therewith 5 as a unit for resiliently supporting the piston in its cylinder.

5. A suction intensifier comprising a unitary body having a cylinder, a fluid pressure responsive piston operable in the cylinder, a 0 delivery passage in the body with which the cylinder communicates, an injector nozzle in the body discharging into the passage and defining with said passage an aspirator chamber, a valve for opening and closing said injector nozzle, said piston having a rod which carries said valve, and a spring encircling the piston rod and confined between the valve and a fixed part of the body.

6. A suction intensifier comprising a unitary body having a cylinder, a piston operable in the cylinder, a delivery passage in the body with which the cylinder communicates, an injector nozzle in the body discharging into the passage and defining with said 5 passage an aspirator chamber, a valve for opening and closing said injector nozzle, said piston having a reduced rod to which said valve is connected, a spring encircling the rod, a spring supporting plate on said rod 0 between the spring and the piston and extending radially beyond the latter for engaging a part of said body to support the piston therefrom and through the spring.

7. A suction intensifier for the suction lines 5 of automobile accessories, comprising a body having an injector nozzle discharging across an aspirator chamber into a delivery passage, said delivery passage being connectible to the intake manifold and said chamber being connectible to the accessory, a cylinder formed in the body and having its inner end communicating with the delivery passage, a piston operable in the cylinder, a valve for the injector nozzle having a part connected 0 to said piston for movement therewith as a unit, and means for urging said piston and valve as a unit to a position to open the injector nozzle, whereby suction maintaining in the intake manifold may be communicated 5 through the delivery passage to the cylinder to move said piston and valve as a unit to a position to close the injector nozzle.

8. A suction intensifier for the suction lines 0 of automobile accessories, comprising a body having an injector nozzle discharging across an aspirator chamber into a delivery passage, a cylinder formed in the body and having its inner end communicating with the delivery passage, a piston operable in the cylinder, a valve having an extension provided with a slot, said piston having a rod portion having a part receivable in the slot of said valve extension for detachably connecting the valve to the piston to be operated thereby, and resilient means engaging the valve extension and

a fixed part of the body for holding the extension of the valve having the slot against the part of the rod portion receivable in the slot for preventing accidental displacement of the rod portion and the valve and for resiliently supporting the valve and piston as a unit.

9. A suction intensifier for a suction line extending between a source of suction and a suction operated accessory, comprising a body having a Venturi passage therethrough and a chamber communicating with the delivery side thereof, a fluid pressure responsive unit including a valve for controlling the passage of atmospheric air through the injector portion of the Venturi passage, said unit being movable as a unit, and resilient means urging the valve to its inoperative position.
